Attorney

UNITED STATES PATENT OFFICE

LEE SING FOO, OF MANCHESTER, NEW HAMPSHIRE

FUSE

Application filed May 7, 1927. Serial No. 189,588.

My invention relates to fuses and more particularly to electric fuses adapted for use in house current.

An important object of the invention is to provide a fuse of this character provided with a plurality of fusible links which may be automatically moved into the electric circuit so as to provide an unbroken fusible link should one of the links become fused.

10 A further object is to provide a fuse plug having a fuse link magazine rotatably mounted therein and operated by a link arranged within the plug whereby it successively moves the link into the circuit as the same becomes 15 broken.

Another object is to provide a device of this character of relatively simple construction, efficient in performance, easily accessible for the renewal of the broken link and 20 inexpensive to manufacture.

Other objects and advantages reside in the special construction, combination and arrangement of the various elements forming the invention as more fully hereinafter described and claimed, reference being had to the accompanying drawings, forming part hereof wherein like numerals refer to like parts throughout, and in which:—

Figure 1 is a longitudinal sectional view, 30 Figure 2 is a transverse sectional view taken along the line 2—2 of Figure 1,

Figure 3 is an inner end view of the rotating magazine, and

Figure 4 is an end elevational view of the 35 outer end of the magazine showing the fuse indicating indicia.

Referring now to the drawings, I have shown my invention comprising a fuse plug body 5 preferably constructed of porcelain or other non-conductive material and of substantially hollow construction throughout. One end of the body is reduced and provided with a metallic threaded sleeve 6 adapted to be fitted within the electric socket and forming one of the contacts for the electric circuit. A pin 7 is longitudinally arranged within the plug having a head 8 forming the other contact for the circuit. The opposite end of the pin is inserted in a bore formed within a fuse link magazine 9 arranged within the body

and rotatable upon the pin. The outer end of this magazine is provided with a recess within which the pin partially extends and is secured therein by a screw 10 threadedly inserted in the end of the pin. A spring 11 is arranged upon the end of the pin and retained under pressure by a washer 12 secured by the screw whereby to tensionally hold the magazine within the plug.

Flanges 13 are formed at each end of the magazine having openings formed therein and adapted to receive the opposite end of fusible link 14. The end of the link 15 carried by the outer flange is secured thereto by a screw 16 and the opposite end of the link 17 extends slightly beyond the edge of the flange so as to form a contact with a brush 18 slidably arranged within a recess at the reduced end of the plug and having its ends rounded in order to permit the sliding of the end of the link 17 thereover. A pin 19 is formed on the brush and is connected to the threaded sleeve 6 by means of a short wire 20. A spring 21 arranged within the recess forces the brush in contact with the end of the link 17 and permits the riding of the link thereover upon the rotation of the magazine.

Upon the outermost end of the magazine is arranged a metallic disc 22, secured thereto by the screws 16. This is provided with a centrally disposed well 23 having an opening through which the end of the pin 7 is inserted. A cap 24 is fitted over the end of the plug having an opening 25 formed therein, the opening permitting inspection within the plug so as to permit the reading of indicia arranged upon the face of the disc 22. The indicia is arranged to correspond to the links carried by the magazine.

At the inner end of the magazine is arranged a spring 27 having one end secured to the magazine and the opposite end secured to the plug, the spring being tensionally secured so as to rotate the magazine within the plug. A stop screw 28 is adapted to be inserted through an opening in the side wall of the plug so that the end thereof will engage the links whereby to prevent rotation of the magazine. The portion of the link engaged by the pin is provided with a weakened section

so that such portion of the link will be the first to become fused and the pin is arranged to engage the link which is in immediate contact with the brush 18, such link constituting the one in circuit. Should such links become fused the next succeeding link is thereupon moved into position and retained by the pin.

5 In the present disclosure of the invention I have arranged the magazine with six links although it is to be understood that this number may be increased or decreased as desired. The indicia on the disc 22 corresponds to the number of the links and such indicia is adapted to register with the opening 25 formed in the cap. When placing the fuse in use the magazine is moved so that the highest number on the disc will register with such openings and the link corresponding thereto is then secured by the pin 28. As the links become fused the number on the disc appearing opposite the opening will indicate the number of links which remain unbroken. The inner end of the magazine is provided with a flange 26 adapted to space the end of the magazine away from the body and a radially extending shoulder 26' is formed at one side of the flange and disposed in the path of the brush 18 to stop the further rotation of the magazine after the same completes one revolution upon the fusing of all of the links 14.

20 30 It is obvious from the foregoing that my invention is susceptible to various changes and modifications without departing from the spirit thereof or the scope of the appended claim, and I accordingly claim all such forms to which I am entitled.

I claim:

40 A fuse plug comprising a body having electric contacts arranged therein, a magazine rotatably mounted therein having a tensionally retained spring attached thereto for actuating the same, a plurality of fusible links removably carried by said magazine in constant engagement with one of said contacts, 45 and successively movable into position for engagement with said other contact, a slidably mounted contacting pin carried by the body engaging said other contact and yieldably retained in the path of movement of said links 50 for engagement thereby, and stop means extending through the wall of the body and adjustable from the outside thereof for retaining one of said links in engagement with said contacting pin, said magazine having indicating means arranged thereon associated with the link, whereby to show which of the links is in contacting position.

55 In testimony whereof I affix my signature.
LEE SING FOO.
